DISPLACEABLE ROTARY FURNACE

Kurt Rudolf Göhre and Paul Jordan, Frankfort-on-the-Main, Germany, assignors to American Lurgi Corporation, New York, N. Y., a corporation of New York

Application March 7, 1939, Serial No. 260,248
In Germany March 9, 1938

7 Claims. (Cl. 263—16)

The present invention relates to rotary furnaces, and, more particularly, to a fuel-fired rotary furnace of displaceable character for carrying out chemical and metallurgical operations.

It has been already proposed to employ rotary tubular furnaces equipped with gas, oil or coal dust heating for carrying out various chemical and metallurgical operations such as the melting and refining of metals and metallurgical products, the volatilization of metals, and for carrying out chemical treatments of various character. These tubular furnaces were generally provided with openings in the side walls thereof for the introduction of material to be treated thereinto and for the removal of treated materials therefrom. It was also suggested to provide furnace heads of displaceable character, or to mount the complete body of the furnace on a rotatable disc so that by the relative displacement of the furnace body and heads the furnace ports at the ends thereof could be made free and the desired operations could be carried out therethrough. To permit withdrawal of slag or the removal of the treated materials through the end openings of the furnace, which also served for the introduction of the heating medium and for the discharge of the furnace gases, the furnaces were also frequently equipped with tilting devices. Tilting of these furnaces was generally accomplished by mounting the complete furnace including its supporting rollers and their frame on axles or the furnace was provided laterally or under its supporting bearings with a cradle or similar supporting structure which was instrumental in transmitting the tilting displacement to the furnace body proper. These conventional arrangements had the disadvantage that they could not be employed in a simple and economical manner for furnaces of large dimensions. As a matter of fact, there were numerous cases when this type of construction could not be employed at all. Thus, it was impossible to employ displaceable furnace heads when it was desired to preheat the combustion air, or the fuel gas, or both, by means of regenerative or recuperative chambers.

It is an object of the present invention to provide a fuel-fired furnace of the rotary tubular type which eliminates the disadvantages and inconveniences of these conventional furnace installations.

It is another object of the present invention to provide a fuel-fired rotary tubular furnace of novel and improved character which makes it possible to carry out all chemical or metallurgical

operations desired in the treatment of the materials contemplated in a simple, efficient and fool-proof manner.

It is a further object of the invention to provide a rotary tubular furnace installation involving a rotary tube adapted to be displaced into a plurality of parallel-spaced positions and which is capable of treating large quantities of charge materials.

The invention also contemplates a rotary tube 10 furnace installation involving regenerative chambers which is simple in construction, efficient and fool-proof in operation, and which may be installed and operated at a low cost.

Other and further objects and advantages of the invention will become apparent from the following description taken in conjunction with the accompanying drawing in which—

Fig. 1 illustrates a top elevational view of a furnace installation embodying the principles of 20 the present invention;

Fig. 2 depicts a vertical sectional view somewhat diagrammatic in character taken on line a—a of Fig. 1;

Fig. 3 shows a side elevational view of the furnace embodying the invention in cooperating position with one of the auxiliary furnace heads;

Fig. 4 illustrates an end elevation of the furnace shown in Figs. 1 to 3 together with its supporting rollers and carriage; and

Fig. 5 is a side elevational view of the furnace of the invention in its tilted position.

Broadly stated, according to the principles of the invention, a fuel-fired rotary furnace of the tubular type is provided which including its supporting rollers is mounted on a supporting structure. The furnace is provided with openings or ports located at both ends thereof. The supporting structure of the furnace is mounted on wheels which can roll on rails so that the complete furnace may be displaced in a direction vertical to its longitudinal axis for the purpose of charging, drawing slag, discharging and for carrying out other operations. Normally, the furnace has its ports resting between a pair of stationary furnace heads which may be connected with regenerative or recuperative chambers and are operated when it is desired to obtain very high temperatures, as is the case, for example, when melting down an ore or metal. During other 50 operations, such as when drawing slag, charging and discharging the furnace, no high temperatures are needed. However, especially during charging, which always requires some time, it is advantageous to heat the furnace even in its 55

position when it is removed from the main furnace heads. According to the invention, this is accomplished by means of auxiliary heating devices and auxiliary furnace heads.

Generally speaking, for reasons of heat economy, the furnaces contemplated by the invention have an accentuated length and consequently have to be charged from both ends in view of the fact that the length of the charging arms or devices is insufficient for introducing the charge material throughout the full length of the furnace. Therefore, it is preferred to successively charge the furnace from both ends. For example, the furnace may first be displaced into cooperating position with an auxiliary furnace head disposed at the left end thereof while an auxiliary burner or heating device is introduced through the upper portion of the right end of the furnace in such a position that it does not interfere with the introduction of the charging device from the same end. After the right half of the furnace has been charged, the furnace is again displaced into another parallel-spaced position in which its right end is in alignment with a second auxiliary furnace head, while another burner and another charging device are introduced into the furnace from the left end thereof. Preferably, both auxiliary furnace heads are in communication with the regenerative chambers on the same side of the furnace in order to introduce the hot furnace gases into the regenerative chambers and thereby to prevent undesirable cooling of said chambers. This communication is established by means of suitable channels or conduits provided between the main furnace heads and the auxiliary heads and through which the flow of gases may be controlled by means of dampers or slide valves.

For the purpose of carrying out certain operations such as discharging the contents of the furnace, drawing slag, and the like, it is advantageous to tilt the furnace in a vertical plane. This tilting displacement about a horizontal axis at right angles to the longitudinal axis of the furnace may be accomplished by providing an upward inclination of one of the rails upon which the furnace is laterally displaced and in some cases also providing a downward inclination of the other one of such rails. Thus, when the furnace on its wheeled carriage is rolled to this inclined portion of the rails, it will be automatically tilted. The other ends of the rails may be provided with inclinations of opposite direction so that the furnace will be tilted in the opposite sense when laterally displaced into its other extreme position. The tilting of the furnace structure is also advantageous during the charging operation, in order to introduce the charge material from a platform into the furnace in its inclined position. It is also possible to provide a platform of a pivotally mounted character to further facilitate carrying out the charging operation.

Referring now more particularly to Figs. 1 and 2 of the drawing, reference character 1 denotes the body of the furnace cooperating with main stationary furnace heads 2 and 3 which are respectively connected with regenerative chambers 4 and 5 and 6 and 7 which serve for preheating the gas and the combustion air, and for recovering the heat of the furnace gases. Reference character 8 denotes to furnace body indicated in broken lines laterally displaced into cooperating position with auxiliary furnace head 14 and with auxiliary burner 12, while reference

character 9 denotes the furnace shown in broken lines as displaced into cooperating position with auxiliary furnace head 10 and auxiliary burner 13. Auxiliary furnace head 11 is connected to regenerative chambers 4 and 5 by means of conduit 14 and auxiliary furnace head 10 is connected with regenerative chambers 6 and 7 by means of conduit or channel 15. Connecting conduits or channels 14 and 15 may be shut off by means of dampers or slide valves 16 and 17, 10 respectively. Reference characters 18 and 19 denote the displaceable charging machines.

Fig. 2 illustrates furnace 1 in cooperating position with the main furnace heads 2 and 3 and regenerative chambers 5 and 7 which serve for preheating the fuel gas and the combustion air and for recovering the heat of the furnace gases, respectively. Supporting rolls 20 and their associated frame are mounted on a supporting frame or carriage 21 provided with rollers or wheels 22 and 23 which can roll on rails 24 and 25. Fig. 3 depicts furnace body 1 in one of its laterally displaced positions in which it is in cooperation with auxiliary furnace head 11, auxiliary burner 12 and charging machine or carriage 18.

As it will be best observed from Fig. 4, two wheels or rollers 22 and 26 are provided at one side of the supporting frame or carriage 21 and only one wheel or roller 23 is provided opposite to the same. Fig. 4 also clearly indicates the upwardly and downwardly inclined arrangement of the rails, rail 24 having an upward inclination, and rail 25 having a downward inclination. In all figures the driving means of the supporting rolls of the furnace have been omitted for the sake of simplicity.

Fig. 5 shows the furnace in the inclined position resting on the inclined portions of rails 24 and 25 beyond the furnace heads. Reference character 27 denotes a disc or roller rotatably mounted on the lower portion of furnace carriage 21 which is engaged by inclined rails 28 and 29 to prevent sliding off of the furnace from rails 24 and 25 in the lateral direction. To assure greater stability, preferably 2 or 3 wheels or rollers of this type are provided on the carriage. On the upper portion of carriage 21 are rotatably mounted rollers 30 and 31 which in the inclined position of the furnace engage the runners of the furnace body. When the furnace is tilted to the left, roller 31, when the furnace is tilted to the right, roller 30 will take up the lateral stresses and will prevent the furnace from sliding off from its supporting rollers. Fig. 5 also illustrates a charging platform 32 which is pivotally mounted at its front edge in pivots 33. The other end of platform 32 may be lifted up by means of a set of pulleys 34 whereby the charge material resting on the platform may be caused to slide into the furnace through charging spout 35. The treated material or residue may be discharged from the furnace into a bucket or ladle 36 which is preferably mounted on wheels.

From the preceding description the operation of the improved furnace installation will be readily understood by those skilled in the art. Assuming that the contents of the furnace have just been discharged in the inclined position thereof (Fig. 5), new charge material is first introduced into the furnace by means of pivotally mounted charging platform 32 and charging spout 35. Preferably, small-sized and light charge material is charged through this charging spout. Hereafter, the furnace is displaced,

for example, in front of auxiliary head 11, damper 16 of conduit 14 is opened and the auxiliary burner 12 is introduced into the furnace. The furnace is now charged by means of charging device 18. After the right half of the furnace has been sufficiently charged, damper 16 is closed and the furnace is laterally displaced before auxiliary furnace head 10. Damper 17 in conduit 15 is opened and the other auxiliary burner 13 is placed into operation. This is followed by charging the left side of the furnace by means of charging device 19. After also this charging operation has been finished, burner 13 is removed, damper 17 is shut and the furnace body is displaced on its carriage between main furnace heads 2 and 3 and the main heating means are actuated through regenerative chambers 4, 5 and 6, 7, respectively. At the same time the furnace is rotated around its longitudinal axis in the conventional manner. This is continued until the charge is melted down or until the desired chemical or metallurgical treatment is finished. In order to carry out special treatments such as poling or refining of copper, addition of desulfurizing and refining agents and of alloying constituents in steel production, the furnace may again be displaced into cooperative position with one of the auxiliary furnace heads 10 or 11, and, if necessary, may be heated by means of auxiliary burners 12 or 13. Finally, the furnace may be again displaced into its inclined position for withdrawing the material therefrom into a bucket or ladle mounted on wheels.

Although the present invention has been described in connection with a preferred embodiment thereof, variations and modifications may be resorted to by those skilled in the art without departing from the principles of the present invention. I consider all of these variations and modifications as within the true spirit and scope of the present invention as disclosed in the foregoing description and defined by the appended claims.

We claim:

5. 1. In a rotary furnace for carrying out chemical and metallurgical operations, the combination comprising a rotatable chamber, ports located at both ends thereof, means for rotatably supporting said chamber, means for laterally displacing said chamber, a plurality of stationary main furnace heads adapted to cooperate with said chamber in predetermined positions thereof, and a plurality of auxiliary devices including auxiliary furnace heads, auxiliary burners, charging and casting devices adapted to cooperate with said chamber in other predetermined positions thereof.

2. In a rotary furnace for carrying out chemical and metallurgical operations, the combination comprising a rotatable chamber, ports located at both ends thereof, means for rotatably supporting said chamber, a wheeled carriage for carrying said rotatably mounted chamber and being adapted to be rolled on rails to laterally displace said chamber into a plurality of positions, a pair of main furnace heads adapted to cooperate with said ports in a predetermined position of said chamber for passing heating gases longitudinally through said chamber, regenerative chambers connected to each of said main furnace heads for preheating said gases, and a plurality of auxiliary devices including auxiliary furnace heads, auxiliary burners, charging and casting devices adapted to co-

operate with said chamber in other predetermined positions thereof.

3. In a rotary furnace for carrying out chemical and metallurgical operations, the combination comprising a rotatable chamber, ports located at both ends thereof, means for rotating said chamber around the horizontal axis thereof, means for laterally displacing said chamber in a direction perpendicular to said axis, a pair of stationary main furnace heads adapted to register with the ports in said chamber in a predetermined lateral position thereof for passing heating gases longitudinally therethrough, regenerative chambers connected to each of said furnace heads for preheating said gases and for recovering heat therefrom, an auxiliary furnace head provided at each end of said chamber in staggered position respectively connected to said main furnace heads, means for controlling the flow of gases from said auxiliary heads to said main furnace heads, and an auxiliary burner opposite to each of said auxiliary heads and adapted to cooperate therewith to pass heating gases through said chamber in other predetermined positions thereof.

4. In a rotary furnace for carrying out chemical and metallurgical operations, the combination comprising a rotatable chamber, ports located at both ends thereof, means for rotating said chamber around the horizontal axis thereof, means including a wheeled supporting carriage and a pair of rails for laterally displacing said chamber in a direction perpendicular to said axis, a pair of stationary main furnace heads adapted to register with the ports in said chamber in a predetermined lateral position thereof for passing heating gases longitudinally therethrough, and a plurality of auxiliary devices including auxiliary furnace heads with said chamber, auxiliary burners and charging devices adapted to cooperate with said chamber in other predetermined positions thereof, said pair of rails supporting said wheeled carriage having at least one portion in which the rails have a different elevation to cause tilting displacement of said carriage and of said chamber.

5. In a rotary furnace for carrying out chemical and metallurgical operations, the combination comprising a rotatable chamber, ports located at both ends thereof, means for rotating said chamber around the horizontal axis thereof, means including a wheeled supporting carriage and a pair of rails for laterally displacing said chamber in a direction perpendicular to said axis, a pair of stationary main furnace heads adapted to register with the ports in said chamber in a predetermined lateral position thereof for passing heating gases longitudinally therethrough, a plurality of auxiliary devices including auxiliary furnace heads, auxiliary burners, charging and casting machines adapted to cooperate with said chamber in other predetermined positions thereof, said pair of rails having at least one portion in which the rails have a different elevation to cause tilting displacement of said carriage and of said chamber, and means operative in the tilted position of said chamber to prevent sliding off of said carriage from said rails.

6. In a rotary furnace for carrying out chemical and metallurgical operations, the combination comprising a rotatable chamber, ports located at both ends thereof, a wheeled carriage for supporting said chamber, means for rotating said chamber around its horizontal axis, means including rails for the wheels of said carriage for laterally displacing said chamber in a direction

perpendicular to said axis, a pair of stationary main furnace heads adapted to cooperate with said ports in a predetermined position of said chamber for passing heating gases longitudinally through said chamber and to heat said chamber to high temperatures, an auxiliary furnace head located in staggered position at each end of said chamber and respectively connected to said main furnace heads, a displaceable charging device at each end of said chamber for alternately charging said chamber from both ends thereof, and an auxiliary burner opposite to each auxiliary furnace head and adapted to cooperate therewith in other predetermined positions of said chamber to maintain its temperature during the charging operation.

7. In a rotary furnace for carrying out chemical and metallurgical operations, the combination comprising a rotatable chamber, ports located at both ends thereof, a wheeled carriage for supporting said chamber, means including a plurality of runners and rollers for rotating said chamber around its horizontal axis, a pair of rails for the wheels of said carriage for laterally displacing said chamber in a direction per-

pendicular to said axis, said rails having at least one alternately inclined portion to cause tilting of said chamber, a pair of stationary main furnace heads adapted to register with said ports in a predetermined position of said chamber for passing heating gases longitudinally through said chamber, an auxiliary furnace head located in staggered position at each end of said chamber and respectively connected to said main furnace heads, an auxiliary burner opposite to each auxiliary furnace head and adapted to cooperate therewith in other predetermined positions of said chamber, a disk rotatably mounted on the lower portion of said carriage in a substantially horizontal plane, a pair of supporting rails laterally engaging the circumference of said disk in the tilted position of said carriage to prevent sliding off of said carriage from its rails, and a plurality of rollers rotatably mounted on the upper portion of said carriage and adapted to laterally engage the runners of said chamber to maintain the same on its supporting rollers in the tilted position thereof.
